UNITED STATES PATENT OFFICE.

ALBERT H. MORTON, OF LOWELL, MASSACHUSETTS.

SPINNING-FRAME.

1,163,552.

Specification of Letters Patent.

Patented Dec. 7, 1915.

Application filed January 16, 1913. Serial No. 742,362.

To all whom it may concern:

Be it known that I, ALBERT H. MORTON, a citizen of the United States, residing at Lowell, in the county of Middlesex and State of Massachusetts, have invented certain new and useful Improvements in Spinning-Frames; and I do hereby declare the following to be a full, clear, and exact description of the invention, such as will enable others skilled in the art to which it appertains to make and use the same.

The present invention relates to spinning frames and the like, and more particularly to top roll weighting mechanisms therefor.

The object of the present invention is to reorganize and improve the spinning frame in respect to the top roll weighting mechanisms for the drawing rolls.

In the companion application Serial No. 742,361, filed of even date herewith, there are illustrated and described two forms of top roll weighting mechanisms. In that application, specific claims to one form of such mechanisms are presented. In this application specific claims to the other form of such mechanisms are presented.

In the accompanying drawings illustrating the preferred form of the invention, Figure 1 is a sectional elevation of a portion 30 of the spinning frame showing the top roll weighting mechanism; Fig. 2 is a front elevation of the same; and Figs. 3 and 4 illustrate details of construction hereinafter referred to.

Referring to the accompanying drawings, the mechanism is described as follows:

The drawing rolls are supported in the roll stand 1 mounted on the roller beam 2 of the spinning frame. The back saddle 3 has bearings at its front and rear ends engaging the bearings of the middle and back top rolls. By reference to Fig. 1 it will be observed that this back saddle is provided with a groove 4 in its upper side which receives wicking 5 extending through holes at the front and back bearings to conduct the oil thereto. The back saddle is provided at 6 with a bearing to receive the rear end of the front saddle. The ratio of the distance 40 of the bearing 6 from the middle roll to the distance from it to the back roll is, in the illustrated embodiment, as 2 to 1, so that, for example, if the pressure applied to the bearing 6 were twelve pounds, it would be distributed to the two bearings, four pounds 50 to the middle roll, eight pounds to the back

roll. The front saddle 7 has a bearing at its front end which rests upon the front roll, and another bearing at its rear end which rests upon the bearing 6 of the back saddle. 60 The stirrup 8 consists of a flattened bar which extends through a hole 9 in the front saddle located midway between the front roll and the middle roll and has its bearing end 10 engaging a bearing cavity 11 at 65 the rear of the hole 9. This front saddle has pressure applied to it at the bearing 11 and the ratio of the distance from the bearing 11 to the rear saddle bearing 6 to the distance from the bearing 11 to the front 70 roll is as four to three, so that, for example, if a pressure of twenty-eight pounds were applied to the bearing 10 by the stirrup, it would be distributed between the front and back saddles in the ratio of 16 to 12. Thus 75 the distribution of twenty-eight pounds on the top rolls would be sixteen pounds to the front roll, four pounds to the middle roll and eight pounds to the back roll. Heretofore the point of application of the stirrup 80 to the front saddle has been at a point directly over the opening between the front and middle rolls, and the pull exerted by the stirrup upon the front saddle was exerted in the line of the space between these 85 rolls. In order to obtain sufficient pressure upon the middle and back rolls to cause them to hold the yarn so as to insure its being drawn properly, a very excessive pressure was required to be applied to the 90 stirrup, with the result that an extremely high pressure was applied to the front roll, with injurious effect upon its durability and the durability of the bearings of the stand in which it was supported. The front top 95 rolls were rapidly worn under the severe pressure with which they were pressed against the front bottom roll, requiring frequent renewal to prevent "fluting." The diminution of pressure secured by the present construction greatly prolongs the life 100 of the front top rolls.

The stirrup of the present invention is a round bar, flattened on its front and rear sides, as shown, thereby insuring a stirrup 105 of great rigidity. Its lower end is offset from the main body of the rod a distance equal to the offset of the top end 10, so that the two ends of the stirrup lie in a line intersecting the middle rolls and the pull of the 110 stirrup upon the front saddle is exerted along this line. The lower end of the stir-

rup is acted upon by the weight lever 12 which has a hole at 13 through which the stirrup passes freely. Upon the lower end of the stirrup the adjusting knife-edged nut 14 is screwed. The knife edges of the nut 14 engage the grooves in the sides of the weight lever 12. The front or fulcrum end of the weight lever 12 is convex in plan and provided with a rocking fulcrum surface 15 which engages the hold-down 16. The weight lever 12 is provided with lateral ears 17, or rocker surfaces, which engage lateral guide surfaces of the hold-down and hold the weight lever in proper position and from lateral deflection with consequent mal-positioning of parts. It is observed that the inclination of the weight lever is such as to tend to cause it to move downwardly and to the left as viewed in Fig. 1, in the direction of its length. This tendency is overcome by the engagement of the ears 17 with the hold-down. It will be observed that the rocking fulcrum surface 15 of the weight lever affords a practically frictionless engagement of the weight lever with the hold-down. The ears 17 of the weight lever maintain it in proper position so that the stirrup is properly positioned between the front and middle rolls. By lifting the weight lever 12 the nut 14 may be turned such a number of half revolutions as may be required to either shorten or lengthen the stirrup to compensate for wear or slight inequalities in the dimensions of the parts in order to bring the parts into the correct position of adjustment. This is desirable, because in the manufacture of these devices the expense thereof must be reduced to the lowest possible amount, and cast iron castings are used for the saddles and for the weight lever and hold-down. This conduces to the economy of manufacture without impairing the efficiency of the operation or the durability of the apparatus. The hold-down 16 consists of a base 18 secured by a bolt to the front edge of the roller beam; it has two upright webs 19 united at their tops by a fulcrum plate 20. The hold-down constitutes the point of application, or the fixed fulcrum of the weight lever, and the pull upon the stirrup is secured by applying the weight to the weight lever 12 so as to cause the fulcrum surface 15 to engage the fulcrum plate 20 of the hold-down. The rear edges of the webs 19 coöperate with the end rockers or ears 17 of the weight lever. The front or fulcrum end of the weight lever being convex in plan, engages the webs 19 over small areas only, if at all, and so opposes little friction to the turning of the weight lever on its fulcrum. By providing the weight lever with several rocker surfaces, to wit, the fulcrum surface 15 and the rocker ears 17, the free movement of the weight lever is secured, with the result that the useful effect

of the weight operating upon the weight lever is substantially all transmitted to the top roll saddle, and little is lost in internal friction. This construction of top roll weighting mechanism commends itself favorably to users, not only by reason of the advantages which it possesses over the constructions of the prior art, which are obvious to persons familiar therewith, but also by reason of the fact that it is adapted to old work as well as to new. Thus, for example, it is easily adapted to old spinning frames by simply taking out the former lever screws and applying the hold-downs to the roller beam and securing them in place by a bolt. The hold-downs being applied and bolted in place, the rest of the mechanism is easily applied to the rolls and the substitution is completed. The principal advantage of this specific construction resides in the permanence with which an adjusted position is maintained in the operation of the spinning frame and the facility by which the proper positioning of the weight lever may be secured by screwing up or down the adjusting nut 14 on the lower end of the stirrup.

The present invention is not limited to the illustrated embodiment as it may be embodied in other forms within the scope of the invention as defined in the following claims:

1. A spinning frame or the like having, in combination, drawing rolls and their supporting means, a saddle, a weight lever supported in an inclined position, and a down-hold engaged by the weight lever, said weight lever having end rockers engaging the down-hold to support the lever against endwise movement and lateral deflection, substantially as described.

2. A spinning frame or the like having, in combination, drawing rolls and their supporting means, a saddle, a weight lever provided with a rocker fulcrum surface and laterally disposed rocker ears, a stirrup connecting the saddle and weight lever, and a hold-down rigidly mounted on the roller beam of the spinning frame and provided with two upwardly extending webs united at their upper ends by a fulcrum plate, being adapted to be engaged by the fulcrum surface of the weight lever, and the upwardly extending webs adapted to be engaged by the laterally disposed rocker ears of the weight lever, the whole being constructed and arranged to reduce the friction between them to a minimum.

3. A spinning frame or the like having, in combination, drawing rolls and their supporting means, a saddle, a weight lever, a stirrup connecting the saddle and weight lever, and a down-hold rigidly secured to the roller beam of the frame, said down-hold having two upright webs united at

their tops by the fulcrum plate adapted to be engaged by the fulcrum surface of the weight lever, the fulcrum portion of said weight lever having convex side surfaces, 5 substantially as described.

4. A spinning frame or the like having, in combination, drawing rolls and their supporting means, a saddle, a weight lever provided with a fulcrum surface and ears, a 10 stirrup connecting the saddle and the weight lever, a hold-down comprising a base-plate bolted to the roller beam, two webs extending upwardly from the base, and a fulcrum plate extending between the tops of the 15 webs and provided with a substantially flat fulcrum surface adapted to be engaged by the fulcrum surface of the weight lever, the

webs being adapted to be engaged by the ears of the weight lever so as to support the weight lever against endwise movement. 20

5. A spinning frame or the like having, in combination, drawing rolls and their supporting means, a saddle, a weight lever provided with means adapted to receive the longitudinal thrust of the weight lever for 25 supporting it against lateral deflection, a stirrup connecting the saddle and weight lever and a hold-down for the weight lever, substantially as described.
